UNITED STATES PATENT OFFICE.

CHARLES P. ROSS, OF SEATTLE, WASHINGTON.

ADVERTISING DISPLAY DEVICE.

1,128,522.

Specification of Letters Patent. Patented Feb. 16, 1915.

Application filed April 23, 1914. Serial No. 833,843.

To all whom it may concern:

Be it known that I, CHARLES P. Ross, a citizen of the United States, residing at Seattle, in the county of King and State of Washington, have invented certain new and useful Improvements in Advertising Display Devices, of which the following is a specification.

This invention relates to advertising devices, and has for its object the provision of apparatus designed to exhibit merchandise under an atmosphere of mystery and with so-called magical effect to attract attention and hold the interest of an assemblage of people while displaying the outward appearance of the goods and familiarizing the public with its trade-mark and distinguishing characteristics.

The invention consists in the novel construction of a cabinet for the display of a carton or container of an article to be advertised, the adaptation of devices for collapsing and distending the carton, and the combination therewith of actuating mechanism and apparatus for the timely operation of the various parts and devices, as will be fully described in the following specification, illustrated in the accompanying drawings, and finally set forth in the appended claims.

In said drawings, Figure 1 is a front elevation of an embodiment of my invention, with portions broken away to disclose some of the interior apparatus. Fig. 2 is a side elevation of same with the side wall removed, and showing the base in section disclosing the actuating mechanism therein. Fig. 3 is a similar view to Fig. 2 with the apparatus in another position. Fig. 4 is a fragmentary horizontal sectional view of a detail of the invention. Fig. 5 is a perspective view of a portion of the operating mechanism. Fig. 6 is a perspective view of the device with the cabinet door open and disclosing the carton. Fig. 7 is a view similar to Fig. 6 with the carton masked.

Referring to said views, the reference numeral 5 designates a base having the motor-chamber 6 wherein the motor and power-transmitting mechanism, hereinafter described, is contained. Mounted upon said base and spaced therefrom upon legs 7 is a cabinet comprising an illusion compartment 8 including the greater part of the cabinet and an apparatus compartment 9 at one side thereof of relatively narrow width and oc-

cupying the entire side wall of the cabinet. The cabinet consists in the top and bottom walls 10 and 11, respectively, the front wall 12 having a hinged door 13 opening outwardly, the back wall 15 and the side walls 16 and 17, the latter of which is removable to give access to the apparatus in the compartment 9 between which and the compartment 8 is the party wall 18. The front wall 12 is symmetrically proportioned upon opposite sides of the door so that the door is positioned about midway thereof and the existence of the compartment 9 will be scarcely noticeable. At the rear of said compartment 8 in proximity of the rear wall 15 is a leaf 20 having a hinge-rod 21 at its lower edge pivotally mounted in the opposite side walls 16 and 17 a short distance forwardly of said rear wall and protruding into the compartment 9 where it is provided with a crank-lever 22. Said leaf is arranged to make a relatively close fit about its edges with the adjoining walls of the cabinet both in its vertical position, as shown in Fig. 2, and its horizontal position shown in Fig. 3, wherein it respectively represents to the view the real rear and bottom walls of compartment 8 with sufficient accuracy as seen through the door-opening in the front wall. A folding carton which is designed in size and general appearance after the container of the goods to be advertised, displaying thereon the trademark of the goods in order to familiarize the public with its characteristics, is connected to the rear surface 20¹ of said leaf by its bottom wall 23 to which is hingedly secured the front wall 25. Side walls 26 are hingedly connected to the front wall to fold outwardly, and a top wall 27 is similarly connected to the front wall to fold inwardly when the leaf is elevated to its upright position, as indicated in Fig. 2, and as will be presently explained. A strip 28 is hingedly connected at its opposite ends to the rear face of said front wall 25 of the carton and to the rear wall 15 of the cabinet in substantial parallelism with the leaf 20 so that the front wall 25 of the carton is maintained in vertical position at all times. A link 31 is pivotally connected at its opposite ends to the top wall 27 and said strip substantially in parallelism with the vertical front wall 25 so that said wall 27 follows the movements and inclinations of said strip and folds downwardly as the leaf is elevated into its erect position. The side walls 26 are

each pivotally connected to said strip by links 32, the connections with the said walls being below the elevation of the strip when the carton is in distended condition, as indicated in Fig. 3, so that as the leaf is swung upwardly and the lower portion of the carton approaches the strip, said links push the respective side wall 26 outwardly until they are substantially in parallel planes with the leaf and the links 32 extend in about horizontal directions and at right angles to the strip 28. It will thus be seen that the carton is folded flatwise between the leaf and the back wall 15 to occupy as little space as practicable when the leaf is erect and is distended to the verisimilitude of a container for merchandise when the leaf is in horizontal position. In both cases, as has been stated, the leaf represents the back wall or the bottom of the cabinet as the case may be, and is painted a uniform color and is of as exact a fit as possible to bear out the deception. The front door 13 is arranged to close while the leaf is being swung in either of its said positions and then open thereafter, disclosing the altered condition of the compartment, alternately exhibiting an apparently normal package of goods, and then showing the same compartment empty.

The apparatus for actuating the door and leaf in their proper order is located in the apparatus compartment 9 and may be described as follows: The crank-lever 22 terminates in a right-angular portion 35 which is engaged within a notch 36 of a swinging-arm 37 which is pivoted at 38 in the opposite end of the compartment. A tension coil-spring 40 is connected to said crank-lever to assist the upward swing of said leaf and neutralize the force of gravity therein and maintain it in erect position. A dog 41 is pivoted at one end to a stud 42 which is secured to the wall 18, and at its free end the dog is formed with a flange 43 provided, as shown in Fig. 5, with a slot 43¹. A link 45 connects the swinging end of said dog with said arm 37. 50 represents a vertically disposed operating-rod which is reciprocatively actuated from the motor chamber 6 and which extends through the tubular leg 7¹ so as to be concealed from the spectators. Said rod is vertically reciprocated in a guide 51 which is disposed to be at a distance below the dog 41 and in said slot 43¹ of the latter and is provided with a pin 52 in line with a shoulder 53 of link 45. Said rod is provided in proximity to its upper end with a notch 55 adapted to operatively engage said dog in each of its reciprocating movements, as will presently be described. Said door 13 is pivotally mounted at its lower edge in the side walls of the cabinet and its pivot 56 is formed with a crank-lever 57 and a terminal pin 58 receivable in an angular slot 60 of a bar 61 pivoted at its opposite end. A coil-spring 62 is connected to said pin 58 and tends to draw the lever 57 downwardly to close said door. A lever 63 is adapted to be engaged by pin 52 at the upper extremity of the travel of rod 50, and a lever 65 performs the same office upon the lowermost travel of said rod. Lever 63 is pivoted at 66 and is connected to bar 61 by a link 67, and lever 65 is pivoted to a bracket 68 and connected to said bar at 70. In said motor-chamber, 71 represents the motor, 72 a crank-shaft and 73 operative connections to rotate the latter at a constant uniform speed. A crank-pin 75 is engaged with a slotted head 76 at the lower extremity of rod 50, the slot whereof is designed to communicate an intermittent motion to said rod, the vertical travel of the rod being relatively slight at the two extremities of its movement wherein the door is open, giving time to the onlookers to observe the condition of the exposed compartment, while the period during which the door is closed and the change of position is effected in the leaf 20 is relatively short due to the greater speed given the rod during the intermediate portion of its travel.

The mechanism just described operates in the manner and sequence as follows: Assuming that the apparatus is in the position represented in Fig. 2 wherein the leaf 20 is folded upwardly and the front door 13 is open for the apparently empty condition of compartment 8 to be observed, the rod 50 is in its uppermost position and the pin 52 is in engagement with the lever 63 thereby holding the door closed through its connection with bar 61. Further rotation of the crank-shaft 72 causes the rod 50 to reciprocate downwardly releasing the lever 63, whereat the spring 62 asserts itself to draw downwardly the crank-lever 57 and close the door. Immediately thereafter in the continued movement of the rod, the notch 55 is presented to the flange 43 of said dog, whereupon the resiliency of the rod causes the upper end of the same to be moved rearwardly to engage the dog within the notch and, being thus engaged, the dog is swung downwardly with the rod for a distance sufficient for the link 45 to influence the arm 37 to swing the crank-lever 22 downwardly in opposition to the spring 40 and thereby swing the leaf 20 downwardly into the position illustrated in Fig. 3. The notch 55 thus engages the dog 41 through a sufficient arc of movement to effect the described lowering of the leaf, whereupon in the continued downward movement of the rod the latter yields sufficiently to allow the latter to escape from its connection with the dog and pass on. The link 45 having been lowered, which depresses the shoulder 53, and the lever 65 elevated by the previous movements of the parts, the pin 52 in its continued

downward movement will next engage the said lever 65 which influences the bar 61 to again open the door. The pin 52, while engaging the lever 65, also bears upon the 5 shoulder 53 to positively hold the leaf 20 down against any accidental movement. The parts are now all as shown in Fig. 3 with the slotted head 76 and the connected rod 50 in their lowermost position. It will 10 be seen that the door has been closed and again opened while the leaf has been shifted from its vertical to its horizontal positions. At the same time the carton carried by said 15 leaf has been distended to represent a box or package of goods standing out in plain view of the beholders. The motion of said crank-shaft 72 continuing, the pin 52 is first relieved from its engagement with the lever 65 and the shoulder 53 thereby again allowing 20 the spring 62 to urge the crank-lever 57 downwardly and close the door 13. The notch 55 then again catches the dog 41 and pulls upwardly the arm 37 and causes the leaf 20 to close upwardly. The pin 52 there- 25 upon engages the free end of the lever 63 which is depressed when the door 13 is closed, and again forces the door to open, disclosing an empty cabinet. The door is again closed and the leaf changed to its al- 30 tered position before the door is again opened. It will be noted that at all times the door is closed while the leaf is being shifted from one position to another.

It is thought that the construction of the 35 apparatus and its mode of operation will be clear from the foregoing. The deception to the public and the illusion created may be heightened by various adventitious devices that are foreign to my present purpose and 40 need not be stated here.

The invention is simple in its idea and the apparatus for carrying it out is relatively simple in its construction and eminently practical in its arrangement and operation.

45

Having described my invention, what I claim, is—

1. In an advertising display device, the combination with a cabinet having a front opening door and a plane leaf pivotally mounted within said cabinet adapted to vibrate between a horizontal position and a vertical position, of power-driven mechanism to open and close said door, said mechanism also serving to alternately raise and 55 lower said leaf during the successive closing movements of the door.

2. In an advertising display device, the combination with a cabinet having a front opening door, a plane leaf pivotally mounted within said cabinet adapted to vibrate between a horizontal position and a vertical position, and power-driven mechanism to open and close said door and synchronously vibrate said leaf as said door is closed, of a 60 folding display apparatus secured to said leaf, and connections between said apparatus and a side wall of said cabinet whereby said apparatus is distended at one of the extreme positions of said leaf and folded in 65 relatively parallel planes therewith upon the leaf assuming its opposite extreme position.

Signed at Seattle, Wash., this 17th day of April 1914.

CHARLES P. ROSS.
